(57) **CLAIM**

The ornamental design for a tire pressure gauge, as shown and described.

DESCRIPTION

FIG. 1 is a perspective view of a tire pressure gauge showing our new design;

FIG. 2 is a top elevational view thereof;

FIG. 3 is a bottom elevational view thereof;

FIG. 4 is a left side elevational view thereof, an elevational view of the right side being a mirror image;

FIG. 5 is a front elevational view thereof; and,

FIG. 6 is a rear elevational view thereof.
